Sellars Patent

The subscriber reported to me there Sellars Patent and, making
part of the same containing a description in the words of the said Patent
as much himself of his improvements in the art of paper making
Called the Picturing Machine.

It is known that Thomas French of the Village of Rhine, County
of Dutchess and State of New York, have invented a new and an
useful Improvement in the art of manufacturing paper which has
designated by the name of the Picturing Machine, the use and object
of which are to separate the knot & dirt from the pulp or stuff after
the rags are ground & by one the stuff paper from the reservoir which is
denominated the Stuff Chest into the vat from which it is removed
by hand or by machine with paper which obviates the necessity & labor
of picking the stuff by hand, after they have become dry and more easily
done in the process of finishing, and that the following is a full and
exact description of the machine as invented by me (his).

Of Cylinders 16 inches in Diameter and 14 inches
high (represented) in the annexed drawing, formed of thin Copper or brass
from one eighth to one sixteenth of an inch thick with brass (1/16) as
superiorly thinner either in the or these cylinders as represented in
the left or extending the whole length of the Cylinder except a rim
around the top and bottom about $\frac{1}{4}$ of an inch apart and about $\frac{1}{4}$ of an
inch wide made so to permit the fine pulp to escape & retain the knot
and dirt within. The Cylinder is let into a frame of wood, the instead of thin
Copper or brass with the brass (1/16) as herein before described. Case
or frame of wood having the said cylinder in the following form
so as to project on one side where the opposite side turns up
so that the cylinder is covered by a frame of wood and the top

represented by (D) attached to a piston rod (B) and playing upon the guiding rods (C.C) which extend to each side of the piston rods through holes in the arms of the brackets are made fast to the bottom and top of the box which encloses the Cylinder. The piston rod is guided by a bush (I) sliding on the guiding rods and joined to a connecting rod at a joint (K) by which it is attached to a crank on the end of a fly-wheel by ordinary and appropriate machinery or gearing so as to give to the dasher a force from hundred to six hundred revolutions or dashes of one down in each minute. —

By this rapid motion of the dasher the fine stuff is forced into the crevices or holes in the sides of the Cylinder while the knots, knots, dirt, and imperfectly ground rags are retained in their and prevented from escaping into the vat and are removed at a revolution through a faucet of gall in the bottom of the Cylinder.

The dasher plays within half an inch of the sides of the Cylinder and from about half an inch of the bottom to within 4 or 5 inches of the top. The machine is to be placed at a proper height and distance between the staff (Chest) and the vat or immersion liability on the vat as most convenient. The staff is conveyed over the top of the Cylinder by a conductor of proper size to supply the requisite quantity for a hand on machine vat which may be used.

The Cylinder is enclosed in a close iron box having air or a convector which catches and secures the pulp as it is forced through the crevices and from which it is conveyed by a conductor at one side into the vat. The following is a description of a Minicrusher of the Pulping Machine in operating the fast track for lime stone and supplying a machine that which works the staff box by two engines. It is propelled from a horizontal staff gear with wheels which is connected with the machine which operates the crushing machine and requires about the fifth part of a horse power. If the staff box is made of materials sufficiently strong to stand the weight of the guiding rods force of the dasher propelling the pulping machine will hardly require the use of

Offering can be found paper by hand in the usual manner and this
will be a long process. Also if ball is to be used in finishing, it will also
greatly improve the quality of paper made by machinery as it throw
the stuff into the ball in an agitated state in which state the fibers
are drawn upon the canister instead of long fibers.

The surface will also much smoother and the
wavy character, and the holes made in the sheets in picking with
hairs is prevented.
